PUMP

Samuel Karasick, Mount Vernon, N. Y.

Application August 15, 1936, Serial No. 96,234

29 Claims. (Cl. 230—147)

The present invention relates to rotary pumps, such as compressors and so-called high vacuum pumps.

Prior pumps of this type have not possessed the degree of efficiency desired where large numbers of vessels or envelopes were to be evacuated rapidly, such as in the manufacture of incandescent electric lamps or so-called vacuum tubes. Pumps of this type have also been open to the objection that they became flooded with oil in the event that the attendant failed to shut off the oil supply when the pump was stopped. Such flooding of the pump system with oil has necessitated the disassembling of the pump so that the various parts thereof could be freed from surplus oil, with the resultant delay in production and the high cost of the cleaning operation.

The main feature of the present invention relates to the provision of an efficient rotary pump which has long life, which is of relatively simple design, and which can be manufactured at relatively low cost.

Another feature of the invention relates to a pump in which the stream of gas through the pump passages, does not have to make any sharp turns and in which there are substantially no pockets or voids tending to set up friction and back pressure.

A further feature of the invention relates to a rotary pump system in which the parts thereof and the oil supply thereto are so arranged that the system will not become flooded with oil even though the attendant fails to shut off the oil supply when the pump is stopped.

An additional feature of the invention relates to a rotary pump unit in which means associated with the rotary piston thereof forces the air or gas drawn from the vessel to be evacuated, into the piston chamber wherein the piston in the course of its rotation, compresses this air or gas and forces it out of the pump.

Still another feature of the invention relates to the provision of a multi-unit pump with its units arranged to operate in tandem at high efficiency.

Other features and advantages of the invention will appear from the detailed description and claims when taken with the drawings in which: Fig. 1 is a front elevational view of a multi-unit pump constructed in accordance with the present invention; Fig. 2 is a top plan view of the pump shown in Fig. 1; Fig. 3 is an enlarged longitudinal sectional view of the pump taken on line 3—3 in Fig. 2; Fig. 4 is an enlarged sectional view of the preliminary pump taken on line 4—4 in Fig. 1;

Figs. 5 and 6 are enlarged transverse sectional views of the pump taken respectively on the lines 5—5 and 6—6 in Fig. 1; Fig. 7 is a cross sectional view of the pump taken on line 7—7 in Fig. 2 particularly illustrating the relation of the inlet to the rocking member; Fig. 8 illustrates a sectional view through the pump on the line 8—8 of Fig. 1 and also illustrates a conventional oil supply tank; Fig. 9 is a side elevation of the pistons and the rocker members connected thereto showing the relation of these parts; Fig. 10 is a sectional view taken on the line 10—10 of Fig. 1, with the casing omitted, particularly disclosing the arrangement for lubricating the bearings as well as the piston and rotary element driver of the pumps; Fig. 11 is a detailed sectional view taken on the line 11—11 of Fig. 10 illustrating the lubricating groove between the piston and the driver; Fig. 12 is a fragmentary sectional view taken on the line 12—12 of Fig. 1 disclosing the contour of the inner wall of the sub-chamber and the adjacent surface of the rocker member whereby a minimum amount of gas or air remains in the sub-chamber at the end of each cycle; and Fig. 13 is a horizontal section through the sub-chamber taken on the line 13—13 of Fig. 12.

For a clearer understanding of the invention, reference is made especially to Figs. 1, 2 and 3, wherein there is illustrated a compound pump PF, including a preliminary pump unit P of large capacity and a final pump unit F of smaller capacity, connected in tandem. Thus the capacity of the pump units increases from the final unit to the preliminary unit. It will be appreciated, however, that the invention is not limited to the arrangement herein disclosed but also includes a pump comprising three or more units connected in tandem where higher capacity per unit of time is required, or the pump may comprise but a single unit where a lower capacity per unit of time will satisfy the requirements.

The preliminary pump P includes a casing 10 open at its ends and having its internal surfaces properly shaped and carefully machined to provide a piston chamber and a sub-chamber to be described. The final pump F likewise comprises a casing 11 of similar construction, also open at its ends. The remote ends of the casings 10 and 11 are respectively closed by an end plate 12 and 13. These casings, which are disposed end to end in displaced angular relation of approximately twenty-six degrees, are closed by a common connector plate 14 having openings or passageways cast therein and extending along the principal axis of the plate. These passage-

ways permit cooling air to flow therethrough by convection to prevent overheating of the plate. It will be appreciated that if such cooling of the plate were not provided, it would become overheated to the point where the oil films on its opposite surfaces would be dissipated, with a consequent decrease in the efficiency of the pump units. The connector plate is provided therein with a conduit 19 communicating with the interior of the casings 10 and 11 and also communicating with the inlet pipe 24, to which a vessel may be attached for effecting the preliminary or "rough" evacuation thereof. The end plate 13 of the final pump has an inlet 25 therein communicating with the pipe 26, to which a vessel that has been roughly evacuated, can be connected to effect the final evacuation thereof. The outlet of the pump is in the sub-chamber of the preliminary pump unit P, which outlet communicates through the pipe 27 with an oil tank 31 of conventional design, where the oil vapors condense and the air or gas expelled from the pump escapes through the exhaust 79 to the atmosphere. It will be understood that in practice lamp bulbs or vacuum tubes are exhausted while moving on a conveyor, the exhaust being effected through a valve connected to a "rough" or preliminary manifold and a final manifold. The "rough" manifold is connected to the inlet of the preliminary pump and the final manifold is connected to the inlet of the final pump. The operation of evacuation is usually progressive and the bulbs are given what is termed a "rough" or preliminary evacuation to remove the greater portion of the gas therein and are then subjected to what is termed the final evacuation to exhaust the bulbs completely.

The internal construction of the final pump unit F and the operating parts therein are disclosed especially in Figs. 3, 4, 5, 6 and 7. Since the construction of the preliminary pump unit P and that of the final pump unit F are substantially the same, it will be sufficient to describe the construction of the final pump only. Identical parts of the preliminary pump will be identified by the same reference characters as applied to identical parts of the final pump, except that the corresponding characters designating parts of the preliminary pump will be primed.

50 The interior of the casing 11 is provided, with a compression or piston chamber 41 of cylindrical form, having its ends closed by the end plates 13 and 14, the walls of the chamber being accurately finished. The casing 11 also has an extension 42, 55 the accurately machined internal surfaces of which provide a sub-chamber 43 defined by the arcuate wall 44 and the flattened wall 45, as well as by the end plates 13 and 14.

A cylindrical piston 58 of smaller diameter 60 than the diameter of the piston chamber but of such length that it is adapted to move in oil-sealed engagement with the plates 13 and 14 of the chamber, operates in the casing. The piston, which is hollow, rotates on the rotary driver element 60 eccentrically attached to the shaft 21. This shaft, as best illustrated in Fig. 3, extends through both casings and is journaled in the bearing 22 in the end plate 12 as well as in the bearing 18 in the connector plate 14 and the bearing 23 in the end plate 13. Thus this shaft is common to both pump units and may be driven from any source of power such as an electric motor, not shown. The pistons 58 and 58' are displaced 180 degrees about the shaft 21 (Fig. 6) to mechanically balance the moving parts of the

5 pump units. By this construction the final pump unit is discharging gas while the preliminary pump unit is removing the discharged gas. It will be appreciated that the dimensions of each piston and its rotary course within its piston chamber are such that successive portions of the cylindrical surface of the piston progressively engage the entire cylindrical inner surface of the piston chamber, so that gas is drawn into the piston chamber at the rear of the piston and gas in advance of the piston is forced out of the piston chamber, as the piston advances.

10 The sub-chamber 43, which opens into the piston chamber 41 in the absence of the operating parts of the pump, is separated from the piston chamber by a rocker member 47, having an edge 48 pivotally mounted in a slot 49 in the wall portion 45 of the casing. The rocker member is of such length that it is freely movable with its ends in oil-sealed relation with the end plate 13 20 and the connector plate 14. This rocker member is formed with an overhanging sweep 50 defining a pocket or passage 51 which communicates with the inlet 25 in the end plate 13.

25 The upper surface 54 of the pocket 51 is inclined downwardly and its left end, as illustrated in Fig. 3, is closed by the portion 55 illustrated in dotted lines, so that gas entering the pocket 51 can only pass into the compression chamber and will not escape directly to the outlet portion of the subchamber. The outer surface 52 of the sweep 50 is machined to arcuate form so that it is adapted to slidably engage the arcuate surface 44 of the casing, in oil-sealed relation therewith, as shown especially in Fig. 6. The wall of the 30 casing may be provided with an insert 53 of hardened metal to constitute a surface of the sub-chamber which can be accurately machined to provide a gas-tight fit with the surface 52 of the sweep.

35 The rocker member is pivotally connected to the piston 58 along one edge of the passage 51, by means of a pintle 56 so that as the piston follows its planetary course within the piston chamber, the rocker member will rock the sweep 50 up and 40 down in the sub-chamber. It will be noted that the under surface of the rocker member 47 is machined to provide a curved surface 61 having the same curvature as the periphery of the piston 58, so that when the piston has rotated to 45 the limit of its compression phase, intimate contact will exist between the surface 61 of the rocker member and a substantial portion of the surface of the piston. Thus all gas which has been compressed in advance of the piston will be 50 expelled through the openings 68, and through the valve mechanism in the rocker member (Fig. 6).

55 The valve mechanism, which may be of any conventional form, is herein illustrated (Fig. 5) as including packing 69 superimposed over the openings 68 and a valve plate 71 held in its closed position against the packing by adjustable springs 72. These springs are positioned within threaded caps 73 which enclose the valve guides 62 of the valve plate and which extend through a cover plate 74. Suitable lock nuts are provided to hold the caps 73 in their adjusted position. Although a plurality of holes 68 for the escape of gas through the rocker member is herein 65 illustrated, a single long slot can be substituted therefor.

70 It will be understood that oil must not only be applied to the bearings for proper lubrication but must also be uniformly supplied to the sur- 75

faces of the moving parts to provide an oil seal so the gas will not be by-passed or leak around certain parts of the pump. As shown in Fig. 8, oil for lubrication and sealing is supplied from the oil tank 31 through the pipe 29 which has branches 32 and 33 (see also Fig. 2) to supply oil respectively to the bearings 18 and 22. Each of the pipe branches 32 and 33 comprises a direct feed pipe 34 and the by-pass feed pipe 35, which is provided with a control hand valve 36 whereby the flow of oil therethrough may be regulated.

The oil for effecting the oil seal between the moving parts of the pump is sucked into the interior thereof by the action of the pistons. As shown in Fig. 8, the oil inlet pipe 32 supplies oil through the pipe 35 and the passages 35' in the bearing 18, which passages communicate with the interiors of both piston chambers at points illustrated by the dotted circle 35' (Figs. 5 and 6). These outlets of the passages 35' are off-center with respect to the axis of the rotary course of the pistons 58 and 58'. The oil inlet pipe 33 (Fig. 10) supplies oil through the pipe 35 and a passage 35' in the bearing 22 to the left end of the piston chamber of the preliminary pump unit. The outlet of this last mentioned passage 35' is likewise located in off-center relation with respect to the axis of rotation of the piston 58'. A suitable stuffing box 86 in a housing 87 prevents leakage around the shaft at bearing 22. A roller end-bearing 88 in the casing-bearing 23 for the shaft 21 receives its lubrication from oil that finds its way around the end of piston 58.

At the junction of each of the end surfaces of the piston 58 with its driver 60, there is provided an annular groove 81, and in the end surfaces of the driver there are provided radial grooves 82, leading from the annular grooves to the surface of the shaft 21. By this construction the rotation of the piston causes the mentioned grooves to wipe across the oil orifices and to pick up a small amount of oil each time that the orifices are passed. The pump unit while in operation is developing a high vacuum so that when the oil orifice 35' registers with a groove, the difference of pressure between the oil in the tank 31 and the pressure in the pump results in oil flowing to the pump in an amount regulated by the valves 36.

By this oiling arrangement if the valves in the oil supply line from the oil tank to the pump units P and F are inadvertently left open when the operation of the pump PF is stopped, the pump units will not be flooded with oil. The possibility of flooding is obviated due to the fact that the air pressure in the exhaust side of the sub-chamber of the final pump unit is different from the atmospheric pressure in the exhaust side of the sub-chamber of the preliminary pump unit and when the operation of the pump is stopped, the air pressures in the pump units thus become balanced to "break" the vacuum therein. With the vacuum "broken," that is, with atmospheric pressure prevailing in the pump units, oil will not flow to flood the exhaust system.

It will be noted that the path of flow of gas through the pump units, as represented by the arrows in Fig. 3, is such as to offer a minimum of resistance to the passage of gas, since the guiding surfaces for the gases are free from sharp turns or corners. Attention should be directed to the fact that the wall of the sub-chamber of the final pump unit is curved as indicated at 90, and that the face of the rocker member 47 is tapered from the edge 91 at one end to the edge

92 at the other end (Figs. 5, 6 and 7) so that when this rocker member is in its highest position illustrated in Fig. 7, there is very little gas or oil left in the sub-chamber 43 due to the mentioned curved surface of the casing and due to the tapered surface of the rocker member. The flat face of the rocker member 47' of the preliminary pump unit is not tapered in this manner but the adjacent wall of its sub-chamber 43' is funnel-shaped or tapered toward the exhaust pipe 27 10 (Fig. 4).

In the operation of the pump, the rotation of the shaft 21 causes the pistons 58 and 58' to planetate in their individual piston chambers in 180 degree displaced relation with respect to each other. The planetation of these pistons in turn causes the rocker members 47 and 47' pivotally connected thereto, to rock toward and away from their respective piston chambers in similar displaced relation, so that one member is rocking 20 downward while the other member is rocking upward. The action of the rocker members will be understood by tracing their paths of movement. In the course of one half of the cycle of planetation of each piston, for example, the piston 58, its rocker member 47 rocks downward toward the piston chamber 41 from its high point shown in Fig. 7 to its low point, which is identical with the position of the rocker member 47' of the preliminary pump unit, indicated in dotted lines 30 in this figure. During the remaining half of the cycle, the rocker member 47 rocks upward from this mentioned low point back to the mentioned high point.

Since the upper surface such as 54 of the pocket 35 such as 51 in each rocker member is inclined downward from its related inlet orifice, when its rocker member rocks downward the gas in the pocket is crowded into a rapidly decreasing space, with the result that the movement of gas toward 40 the piston chamber, is accelerated. This action is especially effective as a high vacuum is approached, since the gas then becomes rarified and its flow becomes sluggish.

In order to understand how evacuation is effected by the pump, let it be assumed that the cycle of the pump begins when the movable parts thereof are in approximately the position shown in Fig. 7. Gas from the pipe 26 enters the pocket 51 in the rocker member and as this member descends a short distance during the rotation of its piston, its pocket communicates with the piston chamber and accelerates the movement of the gas into the space 67 (Fig. 5) in this chamber, at the rear of the piston. This continues until the rocker member and piston reach a position corresponding to that occupied by rocker member 47' and piston 58' as indicated in dotted lines in Fig. 7. While this is taking place, the gas in advance of the piston 58, where it has been trapped during the preceding cycle of the pump, is being compressed. As the piston continues to rotate from the mentioned position, the rocker member starts to rise, and the gas in advance of the piston is further compressed, causing it to exhaust through openings 68, past valve 11, into the sub-chamber. The flat tapered face of the rising rocker member forces this exhaust gas into the conduit 19. The compression and exhaust of the gas in advance of the piston continues until 70 the cycle is completed, when the piston 58 and its rocker member move to the position shown in Fig. 7.

At the beginning of the mentioned cycle, the piston 58' and the rocker 47' of the preliminary

pump unit are in the position illustrated in dotted lines in Fig. 7. From this position, the piston 58' rotates to compress the gas ahead of it which has been introduced into the piston chamber 41' during the preceding cycle. This gas as it is compressed is exhausted through valve 71' into the sub-chamber 43'. At this time the rocker member 47' is rising to its high point and therefore its flat face forces this exhaust gas into pipe 27 from which it flows to the oil tank and thence to the atmosphere. When the rocker member 47' reaches its high point it starts to descend, which movement takes place while the final pump unit is exhausting gas into conduit 19. The pocket 51' in the rocker member 47' thus forces this exhaust gas into the space in the piston chamber 41' at the rear piston 58'. As the piston 58' rotates in the course of the succeeding cycle, it expels this last mentioned gas into exhaust pipe 27 as above described.

The operating cycle just described is effected so rapidly that there is practically an uninterrupted flow of gas through the pump units.

It should be particularly pointed out that there is communication between the inlet of the pump unit and a portion of its piston chamber as well as communication between the outlet of this unit and another portion of its piston chamber, during the major portion of each cycle.

It should be noted that gas is supplied to each piston chamber during a portion of the time that the contacting portion of each piston is traveling from a point at one side of the sub-chamber to a point at the other side thereof. By this arrangement a long period of injection of gas into the piston chamber and a long period for exhausting gas therefrom is afforded in each cycle of operation.

The present disclosure is given as an example of one form of the invention but it will be understood that there may be various changes and modifications thereof, except as defined in the following claims, without departing from the spirit of the invention.

What I claim is:

1. A pump of the class described comprising a piston, a piston chamber, and a sub-chamber, an inlet and an outlet in said sub-chamber, an eccentric driver element for operating said piston to effect a movement of gas through said inlet, a member in and rockably mounted with respect to said sub-chamber, a sweep on said member defining a passage flaring axially of said piston chamber, means pivoting the free end of said member to said piston for moving said sweep along the path of travel of said gas to accelerate the movement thereof toward said piston chamber, and means carried by said member for releasing therethrough gas compressed by said piston for discharge through said outlet.

2. A pump of the class described comprising a piston-chamber and a sub-chamber, a piston in said piston chamber, an inlet and an outlet in said sub-chamber, an eccentric driver element for operating said piston to effect a movement of gas through said inlet, a member in and rockably mounted with respect to said sub-chamber, a sweep on said member defining a passage flaring axially of said piston chamber, means pivoting the free end of said member to said piston for moving said sweep along the path of travel of said gas to accelerate the movement thereof toward said piston-chamber, and a valve in said member operable to release therethrough gas

compressed by said piston for escape through said outlet.

3. A pump of the class described comprising a compression-chamber and a sub-chamber, a piston in said compression-chamber, a rocker member separating said chambers, an inlet to said sub-chamber on one side of said member, a passage in said sub-chamber for the travel of gas from said inlet to said compression-chamber, an outlet for said sub-chamber on the other side of said member, a pivot for said rocker-member on the wall of said sub-chamber, a blade having an inclined surface on the free end of said member and defining a passage flaring axially of said piston chamber, means cooperating with said piston for oscillating said rocker-member to move said inclined surface in the path of gas to said compression chamber to accelerate the movement of said gas, and means for releasing therethrough gas compressed by said piston for escape through said outlet.

4. A multiple pump comprising a plurality of casings, each casing having a compression chamber and a sub-chamber, means for securing said casings in endwise relation, a communicating conduit between said sub-chambers, an inlet in one casing, an outlet in the other casing, pistons in said compression chambers, a movable member in the sub-chamber of one casing cooperating with the piston thereof and having a passage flaring longitudinally of said casing and in a direction away from the other casing to deliver gas to the compression chamber of its casing, means on said member for admitting compressed gas to said conduit for delivery to the sub-chamber of the other casing, a second movable member in the sub-chamber of the other casing cooperating with the piston thereof and having a passage flaring in the same direction as that in the first-mentioned movable member to deliver gas from said conduit to the compression chamber of said other casing, and means on said second member for the release of gas from said last mentioned casing.

5. A rotary pump comprising a casing having a cylindrical compression chamber and a sub-chamber, a piston movable in said compression chamber, a rocker arm separating said chambers and provided with an outlet passage therethrough, said sub-chamber having an inlet and an outlet, an eccentric driver element for operating said piston, means for causing an oscillation of said rocker arm during operation of said piston, a passage flaring longitudinally of said casing on one side of said rocker arm for effecting communication with said compression chamber on one side of said piston, and spring controlled valve means carried by said arm for controlling communication through said outlet passage between said outlet and the compression chamber on the other side of said piston.

6. A rotary pump comprising a casing having a cylindrical compression chamber and a sub-chamber, a piston in said compression chamber, a rocker arm dividing said chambers, said sub-chamber having an inlet and an outlet, means for causing an oscillation of said rocker arm during operation of said piston, a passage flaring longitudinally of said casing on one side of said rocker arm for effecting communication with said compression chamber on one side of said piston, said arm having a passage therethrough affording communication with the compression chamber on the other side of said piston, and a spring controlled valve in said passage.

7. A rotary pump comprising a casing having a cylindrical compression chamber and a sub-chamber, a piston in said compression chamber, a rocker arm separating said chambers, said sub-chamber having an inlet and an outlet, means for causing an oscillation of said rocker arm during operation of said piston, said rocker arm having a passage flaring longitudinally of said casing for effecting communication with said compression chamber on one side of said piston, said arm having another passage therethrough affording communication with the compression chamber on the other side of said piston and a valve controlling said passage.
8. A rotary pump comprising a casing having a compression chamber and a sub-chamber, a piston in said compression chamber, said sub-chamber having an inlet and an outlet, a rocker arm pivoted at one side of said sub-chamber, means connecting said arm with said piston to cause an oscillation of said arm upon operation of said piston, said arm having an outlet passage and means defining a passage tapering longitudinally of said casing to accelerate the movement of gases from said inlet to one side of said piston, and spring-controlled means in the outlet passage in said arm for passing gases from the other side of said piston to said outlet.
9. A pump of the class described comprising a casing having a compression chamber and a sub-chamber, an eccentrically mounted piston in said compression chamber, a rocker arm having one end pivoted in the wall of said casing and movable in said sub-chamber, a pocket tapering longitudinally of said casing at the other end of said arm, an inlet to said sub-chamber, means for positioning said pocket in communication with said inlet and in position to deliver gas into said compression chamber, and an outlet from said compression chamber controlled by a valve in said arm.
10. A pump of the class described comprising a casing having a compression chamber and a sub-chamber, an eccentrically mounted piston in said compression chamber, a rocker arm with an outlet opening and having one end pivoted in the wall of said casing and movable in said sub-chamber, a blade on the other end of said arm serving in conjunction with the wall of said sub-chamber to form a pocket flaring longitudinally of said casing, an inlet to said sub-chamber, means for moving said blade to position said pocket in communication with said inlet to receive gas and for moving said blade to accelerate the movement of said gas into said compression chamber, an outlet for said sub-chamber, and means carried in the opening of said arm for releasing compressed gas to said outlet.
11. A pump of the class described comprising a casing having a piston chamber and a sub-chamber, a piston in said piston chamber, a rocker-member in said sub-chamber, means for pivotally mounting one end of said rocker-member in the wall of said sub-chamber, a blade at the other end of the rocker member, said blade operating in conjunction with the walls of said sub-chamber to form a passage flaring longitudinally of said casing, an inlet in said sub-chamber at one end of said passage, said piston being operable to move said rocker member to accelerate the movement of gas from said inlet toward said piston chamber and effect communication between said passage and said piston chamber.
12. A pump of the class described comprising a compression chamber and a sub-chamber, a piston in said compression chamber, a rocker-member separating said chambers, an inlet to said sub-chamber on one side of said member, a passage in said sub-chamber for the travel of gas from said inlet to said compression chamber, an outlet for said sub-chamber on the other side of said member, a pivot for said rocker-member on the outlet side of said sub-chamber, a blade having an inclined surface, flaring longitudinally of said casing, on the free end of said member, means cooperating with said piston for oscillating said rocker-member to move said inclined surface in the path of gas flowing to said compression chamber to accelerate the movement of said gas, and a valve carried by said rocker-member for releasing gas compressed by said piston for escape through said outlet.
13. A pump of the class described comprising a casing having a piston chamber and a sub-chamber, a piston in said piston chamber, a rocker-member in said sub-chamber, means for pivotally mounting one end of said rocker-member in the wall of said sub-chamber, a blade at the other end of the rocker-member, said blade operating in conjunction with the walls of said sub-chamber to form a longitudinally flaring passage, an inlet in said sub-chamber at one end of said passage, means operable in cooperation with said piston to move said rocker-member to carry gas from said inlet toward said piston chamber, means operable upon a movement of said piston to effect communication between said passage and said piston chamber, an outlet in said sub-chamber, and valve means in said rocker-member for affording communication between said outlet and said piston chamber when said piston has moved to compress gas in said piston chamber.
14. A pump of the class described comprising a casing having a piston chamber and a sub-chamber, a piston in said piston chamber, a rocker-member in said sub-chamber, means for pivotally mounting one end of said rocker-member in the wall of said sub-chamber, a blade at the other end of the rocker-member, said blade operating in conjunction with the walls of said sub-chamber to form a passage flaring longitudinally of said casing, an inlet in said sub-chamber at one end of said passage, means operable in cooperation with said piston to move said rocker-member to carry gas from said inlet toward said piston chamber, said piston being operable to effect communication between said passage and said piston chamber, an outlet in said sub-chamber, and a valve in said rocker-member operable under the force of gas compressed by said piston to release said gas for escape through said outlet.
15. A pump of the class described comprising a casing, a rocker-member, a piston chamber in said casing, an inlet passage and an outlet passage for said casing, a piston, a rocker-chamber in said casing, an inlet and an outlet for said rocker-chamber, means for pivoting one end of said rocker-member in a wall of said rocker-chamber with its free end connected to the piston so that it extends across the outlet passage and is swingable to open and close the inlet passage, a blade on the free end of said rocker-member for sweeping gases from said inlet to said piston chamber, and a surface on said blade inclined from said inlet toward said piston chamber to accelerate the movement of said gases toward said piston chamber.
16. A pump of the class described comprising a piston chamber with an inlet passage, an outlet

passage, and a sub-chamber, an inlet and an outlet in said sub-chamber, a piston, means for planetating said piston to effect a movement of gas through said inlet, means in said sub-chamber comprising a valve member with one end pivoted to a wall of said sub-chamber, extending across the piston chamber outlet passage, with its free end movably connected to said piston, swingable to admit to, and cut off gas from, said piston chamber, and formed with a surface inclined toward the piston chamber for accelerating the movement of gas toward said piston chamber, and means in said valve member between its pivoted and piston-connected ends for releasing gas

- 10 compressed by said piston for escape through said outlet passage.
- 15 17. A vacuum pump comprising a generally cylindrical casing with a valve chamber extending therefrom, a hollow cylindrical piston mov-

20 able in said casing, end plates closing said casing, an eccentric rotary driver element carrying said piston, a shaft extending axially of said piston and on which said element is mounted, a valve member pivotally connected to, and serving to 25 separate, said casing from the valve chamber, means pivoting the free end of said member to said piston, whereby said piston is caused to planetate about the axis of said shaft and the valve member to oscillate about its connection 30 with said casing, said valve member having a passage, defined by a blade extending from the free end thereof, and flaring axially of said casing, an inlet port in the end plate closing the end of said casing adjacent the large end of said passage, 35 said piston during movement causing said valve to open and close off said inlet port to the casing on one side of said piston, said pivotal valve member being formed with an outlet passage, and a spring-controlled closure element 40 mounted in said passage for governing the exhaust movement of gas therethrough from the casing on the other side of said piston.

18. A pump comprising a casing with a compression chamber and a valve chamber extending 45 therefrom, a piston movable in said compression chamber, means closing the ends of said casing, a driver element carrying said piston, a shaft on which said driver element is mounted, a valve member pivotally connected to said casing and 50 serving to separate said compression and valve chambers, the free end of said valve member being pivoted to said piston whereby the latter is caused to planetate about the axis of said shaft, and the valve member oscillates about its connection 55 with said casing, said valve member having a passage flaring axially of said casing, an inlet port in the means closing the end of the said casing adjacent the flared end of said passage, said piston during movement causing said valve 60 to open and close off said port, said valve being formed with an outlet passage, and means in said passage for governing the exhaust movement of gas therethrough.

19. A preliminary and final pump assembly 65 comprising two casings, each with a compression chamber and a valve chamber extending therefrom, a piston movable in each compression chamber, means closing the extreme ends of said casings and connecting the adjacent ends, a 70 driver element carrying each piston, a shaft on which said driver elements are mounted out-of-phase with respect to one another, so that gas from the final pump is discharged to the preliminary pump at about the beginning of the 75 latter's piston stroke, a valve member pivotally

connected to each casing and serving to separate the compression and valve chambers thereof, the free end of each valve member being pivoted to its piston whereby the latter is caused to planetate about the axis of said shaft, and the valve member oscillates about the connection with its casing, the valve members having passages flaring in the same direction longitudinally of their casings, with that in the preliminary pump flaring toward the final pump, inlet and connecting 10 ports positioned, respectively, in the means closing the extreme end of the final pump casing adjacent the flared end of its passage, and in the connecting means, said pistons during movement causing their valves to open and close said ports, 15 said valves being formed with outlet passages, and means in said passages for governing the exhaust movement of gas therethrough.

20. A pump of the class described comprising a casing including a piston chamber and a sub- 20 chamber communicating therewith, said sub-chamber having an inlet port in one end and an outlet port in the other end thereof, a piston mounted to planetate in said piston chamber, a rocker member in said subchamber and pivoted 25 at one side to a wall of said subchamber, another side of said rocker member being pivotally connected to said piston whereby said member normally prevents communication between said piston chamber and said outlet port, and valve controlled means in said member effecting communication between said piston chamber and said outlet, a portion of that surface of said rocker member which is within the subchamber and which extends along said valve controlled means, 30 flaring longitudinally of said casing from said outlet to the other end of said member to reduce the effective capacity of said subchamber. 35

21. A pump of the class described comprising a casing including a piston chamber and a sub- 40 chamber communicating therewith, said sub-chamber having an inlet port in one end and an outlet port in the other end thereof, a piston mounted to planetate in said piston chamber, a rocker member in said subchamber and pivoted 45 at one side to a wall of said subchamber, another side of said rocker member being pivotally connected to said piston whereby said member normally prevents communication between said piston chamber and said outlet port, and valve 50 controlled means in said member effecting communication between said piston chamber and said outlet, a portion of the surface of the sub-chamber adjacent said outlet being inclined toward said outlet to reduce the capacity of said 55 subchamber and to direct the flow of fluid from said subchamber to said outlet.

22. A pump of the class described comprising a casing including a piston chamber and a sub- 60 chamber communicating therewith, said sub-chamber having an inlet port in one end and an outlet port in the other end thereof, a piston mounted to planetate in said piston chamber, a rocker member in said subchamber and pivoted 65 at one side to a wall of said subchamber, another side of said rocker member being pivotally connected to said piston whereby said member normally prevents communication between said piston chamber and said outlet port, valve controlled means in said member effecting communication between said piston chamber and said outlet, a portion of the surface of said rocker member which is within said subchamber and which extends along said valve controlled means, 70 flaring longitudinally of said casing from said 75 outlet.

outlet to the other end of said member to reduce the effective capacity of said subchamber, and means adjacent the outlet port end of said subchamber to further reduce the capacity of said subchamber.

23. A pump of the class described comprising a casing including a piston chamber and a subchamber communicating therewith, said subchamber having an inlet port through one end wall thereof and an outlet port through a side wall thereof, a piston mounted to planetate in said piston chamber, a rocker member in said subchamber and pivoted at one side to said side wall of said subchamber, another side of said rocker member being pivotally connected to said piston whereby said member normally prevents communication between said piston chamber and said outlet port, and valve controlled means in said member effecting communication between said piston chamber and said outlet port, the surface of said side wall having a funnel-shaped contour converging toward said outlet port to direct the flow of fluid thereto.

24. A multiple pump of the class described comprising a plurality of casings, each casing having a cylindrical compression chamber and a subchamber, an end plate for securing said casings together in endwise relation with said cylindrical compression chambers disposed in substantially axial alignment and with the subchambers displaced approximately 26° with respect to each other about the common axis of said compression chambers, said end plate closing the adjacent ends of said compression chambers and subchambers and having a conduit therein communicating with said subchambers, an inlet in the subchamber of one casing, an outlet in the subchamber of the other casing, pistons mounted to planetate about the common axis of said compression chambers, one piston being mounted to planetate in each compression chamber, said pistons being displaced approximately 180° with respect to each other, a movable rocker member in each subchamber, the movable rocker member in the subchamber having said inlet being pivotally connected at one side to a wall of its subchamber and at another side to its related piston to prevent direct communication between said inlet and said conduit, the movable rocker member in the subchamber having said outlet being pivotally connected at one side to a wall of its subchamber and at another side to its related piston to prevent direct communication between said conduit and said outlet, and valve controlled means in said rocker members effecting communication between the compression chambers and their related subchambers.

25. A multiple pump comprising a plurality of casings, each casing having a cylindrical compression chamber and a subchamber, communicating with the cylindrical compression chamber, an end plate for securing said casings together in endwise relation and for closing the adjacent ends of said chambers, a conduit in said plate communicating with said subchambers, said plate also having a passage therein communicating with said conduit and with the exterior of said pump, an inlet in one casing, an outlet in the other casing, pistons mounted for planetary movement in said compression chambers, a movable member in the subchamber of one casing cooperating with the piston thereof to deliver gas to the compression chamber thereof, said member having therein a passage providing communication between said inlet and its related

compression chamber, said member having means for releasing gas from its compression chamber to said conduit, a second movable member in the subchamber of the other casing cooperating with the piston thereof to deliver gas from said conduit to the compression chamber of said other casing, said second member having a valve controlled opening therein communicating with said outlet for the release of gas from said last-mentioned casing.

26. A multiple pump for progressively exhausting hollow vessels comprising a preliminary vacuum pump unit and a final vacuum pump unit, each of said units having an inlet and an outlet, said pump units being supported in adjacent relation with the outlet of said final pump unit in approximate alignment with the inlet of said preliminary pump unit, fluid conducting means connecting said pump units, said means having a substantially straight conduit therein connecting the outlet of said final pump unit to the inlet of said preliminary pump unit, said means also having a passage therein communicating with said conduit, said passage being independent of the inlet of said final pump unit and being adapted to be connected to a hollow vessel initially at atmospheric pressure whereby said preliminary pump unit will partially exhaust the same, said inlet of said final pump unit being likewise adapted to be connected to a hollow vessel for further exhaustion which vessel has been partially exhausted by said preliminary pump unit while connected to said passage.

27. A multiple pump for progressively exhausting hollow vessels comprising a preliminary pump unit and a final pump unit, each of said units having a piston chamber and a subchamber communicating therewith, a piston in each of said piston chambers, mounted for planetary movement therein, a common shaft for driving said pistons, each of said subchambers having an inlet and an outlet, a rocker member in each subchamber cooperating with its related piston to prevent direct communication between the inlet and the outlet of its related subchamber, a common end plate securing said units together in endwise relation and closing the adjacent ends of said piston chambers and subchambers, said end plate having a conduit therein connecting the outlet of said final pump unit to the inlet of said preliminary pump unit and also having a passage therein communicating with said conduit and with the exterior of said pump, said passage being independent of the inlet of said final pump unit and being adapted to be connected to a hollow vessel initially at atmospheric pressure whereby said preliminary pump unit will partially exhaust the same, said inlet of said final pump unit being likewise adapted to be connected to a hollow vessel for further exhaustion which vessel has been partially exhausted by said preliminary pump while connected to said passage.

28. A multiple pump including a preliminary pump unit and a final pump unit, each unit comprising a casing having a cylindrical compression chamber and a subchamber communicating therewith, a planetary piston in each compression chamber progressively contacting the inner cylindrical wall thereof to provide inlet and outlet compartments at opposite sides of the line of contact during each cycle of the piston, a rocker member in each subchamber longitudinally dividing each subchamber into an inlet part and an outlet part, each rocker member cooperating with its related piston to prevent di-

- rect communication between the inlet and outlet parts of its respective subchambers, but affording communication between said inlet part and said inlet compartment as well as between 5 said outlet part and said outlet compartment, an end plate for securing said casings together in endwise relation with said cylindrical compression chambers disposed in substantially axial alinement and with the subchambers displaced 10 10 with respect to each other about the common axis of said compression chambers, said end plate closing the adjacent ends of said compression chambers and subchambers and having a conduit therethrough opening into the inlet part of the 15 subchamber of said preliminary pump unit and the outlet part of the subchamber of said final pump unit to provide respectively an inlet port and an outlet port for said subchambers, said inlet port and outlet port being in approximate 20 alinement whereby said conduit is relatively short, an inlet pipe for the inlet part of the subchamber of said final pump unit, and an outlet pipe for the outlet part of the subchamber 25 of said preliminary pump unit.
25. 29. A multiple pump including a preliminary pump unit and a final pump unit, each unit comprising a casing having a cylindrical compression chamber and a subchamber communicating therewith, a planetary piston in each compression 30 chamber progressively contacting the inner cylindrical wall thereof to provide inlet and outlet compartments at opposite sides of the line of contact during each cycle of the piston, a

rocker member in each subchamber longitudinally dividing each subchamber into an inlet part and an outlet part, each rocker member cooperating with its related piston to prevent direct communication between the inlet and outlet 5 parts of its respective subchambers but affording communication between said inlet part and said outlet compartment as well as between said outlet part and said outlet compartment, an end plate for securing said casings together in endwise relation with said cylindrical compression chambers disposed in substantially axial alinement and with the subchambers displaced with 10 respect to each other about the common axis of said compression chambers, said end plate closing the adjacent ends of said compression chambers and subchambers and having a conduit therethrough opening into the inlet part of the subchamber of said preliminary pump unit and into the outlet part of the subchamber of said final pump unit to provide respectively an inlet port and an outlet port for said subchambers, said inlet port and outlet port being in approximate 15 alinement whereby said conduit is relatively short, an inlet pipe for the inlet part of the 20 subchamber of said final pump unit, an outlet pipe for the outlet part of the subchamber of said preliminary pump unit, and a passage in said end plate communicating with said conduit and with the exterior of said multiple pump, said 25 passage being independent of said inlet pipe.

SAMUEL KARASICK.
